UNITED STATES PATENT OFFICE.

JOHANNES BOSS-CONZELMANN, OF OUSTINETTINGEN, GERMANY.

ADDING APPARATUS.

1,154,367.

Specification of Letters Patent. Patented Sept. 21, 1915.

Application filed January 29, 1913. Serial No. 744,866.

To all whom it may concern:

Be it known that I, JOHANNES Boss-CONZELMANN, a citizen of the German Empire, residing at Oustinettingen, in the 5 Kingdom of Wurttemberg, Empire of Germany, have invented certain new and useful Improvements in Adding Apparatus, of which the following is a specification.

This invention relates to a novel construction of adding apparatus, the essential characteristic of which consists in that the addition can be made with as many figures as desired, and nevertheless, only one single row of only nine keys are necessary. In 15 order to render this possible according to the present invention there is interpolated between the adding apparatus of known construction with transfer mechanism, and the axle controlled by the shift keys, which carries the decimal shifting wheels, a special axle upon which likewise decimal gear wheels are arranged adjustable, the number of which is determined by how many placed figures are to be added with the apparatus 20 (in the accompanying drawing the number is seven). These adjustable intermediate wheels can be operated from the outside by special keys and in such a manner that upon depressing the next following key and thereby causing the interposition of the corresponding operated wheels, the previously operated wheel is compulsorily put out of gear. The arrangement of these intermediate wheels has for its object that the 25 unit-ten-hundred-etc., row of the figures to be added together can be added consecutively and the final result of the separate rows of figures remain directly visible at the display points. Consequently, in using 30 the apparatus there is nothing more necessary than at the commencement of the counting, firstly, to put into gear the intermediate wheel of the unit row, that is, to couple together the unit point of the counting apparatus and the axle of the transferring wheel, whereupon by means of the nine shift keys, the unit row is added up. After completion 35 of this calculation the intermediate wheel of the tens row, is put into gear, whereby that of the unit row is automatically put out of gear, so that on the subsequent addition of the tens row, the unit figure obtained remains unaltered. In the same manner the operator proceeds with regard 40 to the other decimal positions.

In the accompanying drawing, the invention is illustrated as follows:

Figure 1 is a longitudinal section on the line A—B of Fig. 2. Fig. 2 is a partial view from above. Fig. 3 is a section on the 60 line C—D of Fig. 2.

In a casing 1 is arranged a counting apparatus of known construction upon an axle 2, the counting rows 3 whereof are visible through peep holes 4 in the lid of the casing. The counting mechanism which in the example described is arranged for seven-place figures possesses a transfer mechanism 5, 6 of known construction and ten-toothed wheels 7. The wheels 7 are connected rigidly with the counting rollers 3 and are provided upon one side with ten pins 5 and upon the other with two pins 6.

The pins 6 engage the gear wheel α after each complete revolution of the wheel 7 or the counting rollers 3. The toothed wheel α revolves loosely upon the axle b and is rigidly connected with a wheel d provided with ten teeth by means of the hub c . This wheel d is positioned in front of the pins 5 of the next higher order wheel 7 and engages with the same. After each complete revolution of a counting roller 3, together with the wheel 7, caused by the pins 6, the wheel α , together with wheel d , are shifted 75 around a tooth, the latter switches the next following wheel 7 and the counting roller 3 one point farther away, and the "decimal shifting mechanism" results therefrom.

Under the counting mechanism there is supported an axle 8 which has nine ten-toothed wheels 9, 10 keyed upon it, of which the part 9 can be brought into engagement with the numeral key 11, while the part 10 stands vertically under the counting mechanism 90 wheels 7, so that the intermediate wheels 13 which are displaceable upon the intermediate axle 12, can be brought into engagement with the wheels 7 and 10. The shifting of the wheels 9, 10 takes place by means of the keys 11, which are provided consecutively with figures from 1 to 9 which can engage 95 in the parts 9 of these wheels. The keys 11 work in sleeves 14, which are pivotally connected at 15 with the rear wall of the casing and they are under the influence of springs 16 in the sleeves 14, which automatically restore them to their normal positions. The front ends of the keys 11 stand under the influence of springs 17 which have the pur- 100 105 110

pose of immediately raising the keys 11 after the shifting is completed and of bringing them out of engagement with the teeth of the wheels 9 before the springs 16 can come into action, so that a turning back of the counting mechanism is impossible.

In order that the keys 11 shall be first completely depressed before their shifting motion is possible and an assured engagement that the shift wheels 9, 10 must follow, they are provided with projections 18 which engage behind projections 19 and only permit an advance of the keys 11 after the same have been depressed until the projections 18 have entirely passed the projections 19. In order not to interfere with the return motion of the keys 11 to the initial position the projections 19 are constructed slightly elastic upward so that the projections 18 can slip past them. For the purpose of insurance against any automatic turning back of the axle 6 there is provided at one side thereof a locking catch 20 working in one direction only.

The displacement of the adjustable intermediate wheels 13 placed upon the intermediate axle 12 is effected by the depression of keys 21, which project above the keys 11 from the front wall of the casing 1 and are numbered consecutively, for instance, from 1 to 7. These keys 21 are pivotally connected at 22 each with one angle lever 24 revolving about the fixed pivots 23, the longer arm of which lever is connected at 25 with a fork 27 engaging over a ring 26 on the intermediate wheel 13, so that on the rotation of the angle lever 24 by the depression of the key 21, a displacement of the wheel 13 takes place to the left, whereupon the same comes into engagement with the counting wheels 7 and the shifting wheels 10. The left displacement of the wheels 13 is limited by the keys 21 striking against the wall of the casing, while their displacement to the right is limited by the pins 28. In order to attain the result that upon the depression of each consecutive key 21, the preceding key 21 is certainly and compulsorily returned to its original position, and the corresponding intermediate wheel 13 is put out of gear, each key 21 is pivotally connected at 31 with an arm 30 revolving on the pivot 29, the free end of which engages against a projecting pin 31 of the next key 21, when the preceding key is in gear, so that upon the depression of the former, the latter is returned by the turning of the arm 30 into its original position and carries with it the corresponding wheel 13. In order that also the last used key 21 after the calculation is ended shall be again moved back, there is arranged a displaceable bar 33, against which the depressed keys 21 rest with the lower end of their projections 32, so that they can be pressed back from the side wall of the cas-

ing 1 into their original position by the raising of the bar 33 running in slot guides 34. A spring 35 tends continuously to restore the bar 33 to its normal position.

The operation of the apparatus is as follows:—Let us assume that the following row of figures is to be added:—

189	189
278	278
9	9
57	57
39	39
128	128
25	25
9	9
367	367
429	429
1469	1469
18	18
128	128
6	6
	—
3151	3151
	80
	75

Before commencing the addition of the units row, the key 21 numbered 1 is depressed so that the corresponding intermediate wheel 13 engages with the corresponding counting wheel 7 of the counting mechanism and also with the shift wheel 9, 10 or its part 10 lying beneath it. Thereby the connection between the counting mechanism and the axle is operated. Hereupon the numeral keys 11 are actuated consecutively corresponding to the numbers of the units row of the figures to be added, whereupon in the peep hole 4 the result 111 appears. Before commencing the addition of the tens, the key 21 which bears the indication 2 is depressed which has for result that the next intermediate wheel 13 is engaged, and at the same time the previous wheel 13 is compulsorily put out of action by the pin 32 and the arm 30. Consequently for the next following addition of the tens row, the last figure 1 of the first obtained result 111 remains unaltered in the unit place. The addition of the tens row follows in the same manner as that of the units row, by actuating the numeral keys 11. The result of this addition is the figure 44 and consequently there appears in the peep hole the figure 551. Hereupon the key 21 which bears the indication 3 is depressed whereby the wheel 13 belonging to the hundreds row is put into gear. The preceding wheel on the other hand is put out of gear in the manner described so that on the addition of the hundreds, the figure 5 in the tens space remains unaltered. The addition of the hundreds row gives the value 16 so that in the peep hole 4 the figure 3151 now appears. The operation is then repeated with the thousands row in the same manner, that is to say, the key 21 which bears the number 4 is now depressed, the corresponding intermediate wheel 13 is put into gear, the previous wheel is put out of gear and there remains in the hundreds row the figure 1 standing. After the thousands row has been added up, as the final result is ob-

- tained there appears the figure 3151. The operator proceeds in exactly the same manner when more than four place figures are to be added as shown in the illustrated example. It is therefore easy with the present invention to add together quickly and reliably any desired amounts of as many decimal places as desired and the final result can be read direct from the peep holes.
- 10 Having now particularly described and ascertained the nature of my said invention and in what manner the same is to be performed, I declare that what I claim is:—
- 15 1. In an adding apparatus, in combination, counting mechanism comprising an axle having toothed wheels mounted thereon, a second axle, pairs of toothed wheels mounted on said second axle, keys for rotating said pairs of wheels, an intermediate axle, intermediate toothed wheels slidingly mounted thereon, said wheels being adapted to be moved into and out of intermeshing relation with said first mentioned and said second mentioned wheels, and keys for actuating said intermediate wheels.
- 20 2. In an adding apparatus, in combination, counting mechanism comprising an axle having toothed wheels mounted thereon, a second axle, pairs of toothed wheels mounted on said second axle, keys for rotating said pairs of wheels, an intermediate axle, intermediate toothed wheels slidingly mounted thereon, said wheels being adapted to be moved into and out of intermeshing relation with said first mentioned and said second mentioned wheels, and keys for actuating said intermediate wheels.
- 25 3. In an adding apparatus, in combination, counting mechanism comprising an axle having toothed wheels mounted thereon, a second axle, pairs of toothed wheels mounted on said second axle, keys for rotating said pairs of wheels, an intermediate axle, intermediate toothed wheels slidingly mounted thereon, said wheels being adapted to be moved into and out of intermeshing relation with said first mentioned and said second mentioned wheels, and keys for actuating said intermediate wheels, and means for restoring any one of said keys to its normal position.
- 30 4. In an adding apparatus, in combination, counting mechanism comprising an axle having toothed wheels mounted thereon, a second axle, pairs of toothed wheels mounted on said second axle, keys for rotating said pairs of wheels, an intermediate

axle, intermediate toothed wheels slidingly mounted thereon, said wheels being adapted to be moved into and out of intermeshing relation with said first mentioned and said second mentioned wheels, and keys for actuating said intermediate wheels, said last mentioned keys being provided with co-acting means whereby actuation of any one of the keys will restore the preceding key to its normal position.

5. In an adding apparatus, in combination, counting mechanism comprising an axle having toothed wheels mounted thereon, a second axle, pairs of toothed wheels mounted on said second axle, keys for rotating said pairs of wheels, an intermediate axle, intermediate toothed wheels slidingly mounted thereon, said wheels being adapted to be moved into and out of intermeshing relation with said first mentioned and said second mentioned wheels, keys for actuating said intermediate wheels, and means for restoring any one of said keys to its normal position.

In testimony whereof I affix my signature in presence of two witnesses.

JOHANNES BOSS-CONZELMANN.
